UNITED STATES PATENT OFFICE.

STUART B. MOORE, OF LA PORTE, TEXAS.

GIRDER.

Application filed July 24, 1923. Serial No. 653,556.

My invention relates to girders and particularly to those fabricated of steel and poured concrete or other suitable plastic material. One object of my invention is to 5 cheapen the cost of girders and I find that the improvements hereinafter described and claimed make it possible to construct a composite steel and concrete girder which will compete in cost with wooden structures, even 10 where the latter are untreated.

A further object of the invention is to improve the construction of composite steel and concrete girders with respect to the distribution of stresses therein, and to render it possible 15 to erect a structure of precast units that will be similar in all requisites to a poured structure without the use of forms.

The invention rests upon the discovery of means whereby condemned or worn-out rail- 20 way rails may be employed as chord members in a composite girder of steel and poured concrete. Old rails, which I find peculiarly suited to the purpose of my invention, are available in ample quantities on every rail- 25 road. The use of such discarded rails effects a two-fold economy, for on the one hand they may be used along the line of the railway, as for example in constructing trestles instead of being scrapped and carried to relatively 30 great distances for the purpose of being utilized as scrap; and on the other hand the availability of such cheap steel reinforcing members for reinforced concrete structures makes it possible for such structures to com- 35 pete with treated or untreated wooden structures, whereas heretofore the expense of bringing specially prepared reinforcing elements from steel plants to the point of use has made reinforced concrete structures far 40 more costly than wooden structures for trestles and the like.

Railway rails of the usual form are not merely utilizable as chord members but are peculiarly suited to the purpose, being of the 45 requisite strength and of a shape which lends itself to the attainment of a new type of fabricated girder in which the stresses are distributed in an advantageous and novel manner. However, although preferring to 50 employ condemned rails for the sake of economy, my invention, in certain of its aspects, contemplates the use of specially prepared steel members in place of the rails. Moreover, while the improvements for the reasons 55 indicated above are of special advantage in the construction of trestles and bridges for

railways, nevertheless my invention is not limited in its application to railway work but may be applied wherever reinforced steel structures may be employed.

In the accompanying drawings the preferred form of my improved girder is illustrated,

Fig. 1 being a side elevation with the concrete partly broken away at one end,

Fig. 2, a transverse sectional view on the line II—II of Fig. 1, and

Fig. 3, a transverse sectional view on the line III—III of Fig. 1.

Referring to the drawings in detail, 1, 2 and 3 designate railway rails of the usual type, having tread portions designated by the reference numerals previously mentioned, web portions, 4, 5 and 6, respectively, and flanges, 7, 8 and 9, respectively. These rails are preferably disposed in the manner shown in the drawings, that is to say, two of the rails, 1 and 2, are inverted and serve as compression members, and rail 3 is bent into the form shown in Fig. 1 and serves as a tension member. The ends of the rail 3 are brought substantially midway between the adjacent ends of the rails 1 and 2 and in this position the three rails are connected or tied together, preferably by transverse pins 10 having on their threaded ends 11 nuts 12, or other means. Preferably fish plates 13 will be applied to the web portions of the rails 1 and 2 by means of rivets 14. The steel frame thus constructed constitutes the chord elements or compression and tension members of a truss, and my invention contemplates that metal web members will be generally dispensed with in my improved truss. Instead of metal web members a monolithic web 15 of concrete or other suitable plastic material is produced by means of a suitable form in the usual manner. It will be observed that the web 15, as illustrated in Fig. 2, conforms in outline to the skeleton frame made up principally of the rails 1, 2 and 3. This is the preferred form of my invention, and I claim as an important feature thereof the relation of the rails to the concrete webs, the flanges of the former constituting a substantially unbroken, enveloping loop or loops around the concrete web in a longitudinal direction, and the upper rails 1 and 2 with the pins 10 further confining the web 15 laterally along its top portion.

With the web constructed in the roughly triangular cross-sectional form shown and

the flanged compression and tension members disposed as shown, a very advantageous distribution of stresses is obtained. The web is confined within the metal frame composed 5 of the rails in such a way as to be incapable of distortion under load stresses without such distortion being opposed by the metal frame or enveloping loops composed of the rails. Similarly, tension stresses applied to the 10 steel members are opposed by the compressive strength of the concrete web. For example, tension stresses on the rail 3 are resisted through the pins 10 by the rails 1 and 2 and the web 15 confined therebetween, 15 not only in a longitudinal but also in a lateral sense.

The distribution of stresses effected by my invention is not to be confused with reinforced concrete structures in which unconnected steel members are imbedded in concrete, or the like. Although in certain respects my proposed construction functions in 20 a manner similar to reinforced concrete in general, nevertheless the special functions 25 hereinbefore pointed out result from the relation of the metal frame and concrete web

as described and as hereinafter claimed. It should be recognized that in reinforced concrete the girder resists the stress because the steel reinforcement is gripped by the concrete 30 and in my girder the stresses are transferred to the concrete because a line of cleavage is developed between the concrete and the steel.

What I claim is:

1. A girder comprising in combination, a 35 concrete web and flanged compression and tension members joined at their ends, the flanges of said members being disposed outwardly and forming an enveloping loop around the web longitudinally.

2. A girder comprising in combination, a concrete web, flanged compression members overlying the upper longitudinal corners of 40 said web, a tension member enveloping said web along its bottom, there being no metal web members, and means connecting the adjacent ends of the compression and tension members.

The foregoing specification signed at Washington, D. C., this 23rd day of July, 50 1923.

STUART B. MOORE.
